UNITED STATES PATENT OFFICE

BENJAMIN TOWNE, OF NEW YORK, N. Y.

CRAYON AND ERASER HOLDER

Application filed March 5, 1927. Serial No. 173,140.

This invention relates to combination crayon holders and erasers and in particular to a device of this character which is especially adapted for use in schoolrooms and while lecturers use chalk for explanation purposes.

A particular object of the invention is to provide a single implement which may be used by a teacher when writing upon a blackboard for holding chalk and an eraser so that during an illustrated discussion, if an error is made, the necessity for interrupting the discussion and finding an eraser will be eliminated.

15 Another particular object of the invention is to provide in combination, an eraser and chalk holder which will be convenient to use and which will prevent the soiling of the hands during the use of the chalk.

20 A still further object of the invention is to provide an eraser in combination with a chalk holder which may be effectively used and which will eliminate the necessity for using a chalk laden eraser which has been used to clean the entire blackboard, as it is well known that erasers in common use soon become impregnated with chalk particles and, with little use, cover the fingers with chalk, which is unpleasant to the touch.

30 To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

40 Figure 1 is a view in elevation of my improved chalk holder and eraser, showing a piece of chalk therein in position to be used.

Figure 2 is a view in sectional elevation showing the connection of the eraser with the body of the implement and the attachment thereto of the chalk holding sleeve, there being shown positioned therein, a piece of chalk ready for use.

Figure 3 is a modified form of chalk jacket used separately and preferably made of paper which can be used to cover a single piece of

chalk and may be discarded after the same becomes soiled, and

Figure 4 is a modified form of the body portion of the combined eraser and chalk holder, the same being provided with an enlarged head which forms a more substantial base for the eraser during the use thereof. 55

the pin 9 is occupying the transversely disposed portion 12 of the slot 10. Another function of this transverse slot is that it provides a corner 13 of the metal or other material forming the chalk holder and in the case of metal, this corner 13 may be bent slightly inward to bear against the body 5 or the chalk 14 which is held in the sleeve 11, thereby providing a frictional contact between the sleeve and its content. Of course, in the construction, as shown, this corner 13 will only engage with the body 5 and will, in having frictional contact therewith at any point, be adjustable longitudinally thereof to expose the lower end of the chalk as the same is used, by retraction of the holder upwardly along the body 5. The chalk 14 can be forced through the tube 11 as the same is moved along the body 5. In this connection, I may provide, if desired, an enlarged head portion 15 on the end of the body 5, this head

portion forming a support for the base 16 of the eraser 17, the enlarged head portion 15 being provided with the threaded extension 18 with which the base 16 of the eraser has threaded connection and through the medium of which the eraser can be secured to the upper end of the body 5.

In my modified form of eraser or crayon holder or jacket, I provide preferably a paper sleeve 19, slotted at its lower end as at 20 and having its lower edge beaded as at 21, the slot 20 and the bead 21 providing therebetween a frictional gripping contact necessary in retaining the jacket in proper position upon the chalk 22, it of course being understood that chalk being a grimy substance, is not only unpleasant to the touch but after using all sorts of colored chalk, as required by an instructor, the different colors and dyes in the chalk become embedded in the skin of the fingers and is very difficult to remove, and in providing this paper jacket 19 for the chalk, the same may be advanced along the chalk exposing the lower end thereof whereby the writing may be carried on without contact with the fingers directly with the chalk. These jackets 19 may be placed on each piece of chalk in use and may be thrown away when they have served their usefulness.

It is evident therefore, that I have provided an improved crayon holder and eraser holder which will eliminate waste of time by the instructor in looking about for an eraser when a mistake is made and one also, which will prevent the fingers from becoming soiled.

It is evident also that I have provided a chalk holding member which may be advanced as the chalk is used so that all of the chalk may be used and thereby waste is eliminated of the short pieces of chalk which are not at present used due to the inability to hold the same while writing.

It is evident also, that I have provided a combined eraser and chalk holder wherein the eraser when worn, may be detached from the holder and may be replaced with a new one.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what I claim as new and desire to secure by United States Letters Patent is:—

A chalk holder comprising a tubular member of uniform diameter and open at both ends, the said member being formed with a longitudinally extending slot having a branch 65 at one end extending in the direction of the

circumference of the member, which member is adapted to have a chalk frictionally fitted into one end thereof and movable therein to project at one end beyond that end of the member remote from the branch of the slot, a stem of cylindrical form fitted slidably and rotatably in the said tubular member and adapted to engage at its inner end against the inner end of the chalk and projecting at its other end beyond the other end of the tubular member, and a stud upon the stem movable in said slot and permitting of adjustment of the stem in the tubular member, when the stud is in the straight portion of the slot, to effect corresponding adjustment of the chalk to project at its first mentioned end beyond the said tubular member, the said stud being engageable in the branch of the slot whereby to hold the said stem against sliding movement in the slot and permit retractive movement of the chalk into the said tubular member.

In testimony whereof I affix my signature.
